DESIGN FOR A CIGARETTE PACKAGE HOLDER

Earl F. Murray and Clare E. Hermann,
Minneapolis, Minn.

Application March 24, 1941, Serial No. 99,824

Term of patent 14 years

To all whom it may concern:

Be it known that we, Earl F. Murray and Clare E. Hermann, citizens of the United States, residing at Minneapolis, in the county of Hennepin and State of Minnesota, have invented a new, original, and ornamental Design for a Cigarette Package Holder, of which the following is a specification, reference being had to the accompanying drawing, forming part thereof.

We claim:

The ornamental design for a cigarette package holder, as shown.

EARL F. MURRAY.
CLARE E. HERMANN.
